(57) CLAIM

The ornamental design for a garment, as shown and described.

DESCRIPTION

FIG. 1 is a front perspective view of a garment showing my new design in an as-worn configuration;

FIG. 2 is a front elevation view thereof;

FIG. 3 is a top plan view thereof;

FIG. 4 is a first side elevation view thereof; and,

FIG. 5 is a second side elevation view thereof.

The long and short broken lines define the bounds of the claimed design, but do not form part of the claimed design. The even-length broken lines shown in the drawings are directed to environment and form no part of the claimed design. In addition, the unshaded regions, demarcated by the even-length broken lines, represent unclaimed portions of the garment and form no part of the claimed design.
